(57) **CLAIM**

The ornamental design of a housing, as shown and described.

DESCRIPTION

FIG. 1 is a front perspective view of the housing, showing my new design;

FIG. 2 is a rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof; and,

FIG. 9 is a perspective view illustrating the housing mounted to a rail.

The details shown in broken lines are for illustrative purposes only and form no part of the claimed design.
